UNITED STATES PATENT OFFICE.

ARTHUR O. AUSTIN, OF BARBERTON, OHIO, ASSIGNOR, BY MESNE ASSIGNMENTS, TO THE OHIO BRASS COMPANY, OF MANSFIELD, OHIO, A CORPORATION OF NEW JERSEY.

INSULATOR.

Application filed June 8, 1921. Serial No. 476,179.

To all whom it may concern:

Be it known that I, ARTHUR O. AUSTIN, a citizen of the United States, residing at Barberton, in the county of Summit and State of Ohio, have invented certain new and useful Improvements in Insulators, of which the following is a specification.

This invention relates to electric insulators, and especially to insulators for high potentials, and has for its object the provision of devices of the class named which shall be of improved construction and operation, and especially which shall have improved means for controlling the electrostatic flux distribution.

The invention is exemplified in the combination and arrangement of parts shown in the accompanying drawings and described in the following specification, and it is more particularly pointed out in the appended claims.

In the drawings—

Fig. 1 is a transverse section of a high tension transmission line showing a string of insulators in elevation having one embodiment of the present invention applied thereto;

Fig. 2 is a vertical sectional view of one of the flux control members illustrated in Fig. 1;

Fig. 3 is an elevation of a different form of control member;

Fig. 4 is an elevation partly in section of another modification of the control member; and

Figs. 5, 6, 7, 8, 9, 10 and 11 show still further modifications of the flux control members.

Fig. 12 shows a side elevation and Fig. 13 a transverse section of a transmission line and a suspension string having another form of flux distributor connected thereto.

In Fig. 1, the numeral 11 designates a portion of a supporting structure, such as a tower for supporting a high tension line. Suspended from the member 11 is a plurality of insulators 12 connected in series, the insulators being of any well-known and approved construction, such as is shown in my prior Patent No. 1,284,976, granted November 19, 1918. A conductor 13 is supported at the lower end of the string of insulators 12 and is secured to the string by a saddle fitting 14. Connected with the

fitting 14 and the conductor 13 are upwardly and outwardly extending flux control rods or horns 15. The horns may extend transversely of the line 13, or may be arranged to extend in the longitudinal direction of the line, or at various angles thereto as occasion may require.

As shown in Fig. 2, the horns 15 are provided with caps or attaching members 16 to which is secured an insulator or dielectric member 17. The member 17 is provided with downwardly extending flanges 18 and 19 which prevent flash-over when the insulator is wet or when under a very high voltage. A suitable pin or fitting 20 is secured in a recess in the upper face of the insulator 17 and carries a metallic rod or pin 21 extending upwardly above the insulator 17. The upper end of the rod 21 may terminate in a knob 22 which in turn is provided with an insulator 23 having downwardly extending flanges 24 and 25. The insulator 23 may be covered by a metallic cap 23', as shown at the right in Fig. 1, or, this cap may be omitted, as shown at the left in that figure. The horn 15 and the extension 21 may be encased in a sheathing of flexible insulating material, such as a rubber hose 26 shown in Fig. 2, or it may be left bare, as illustrated in Fig. 1. It will be understood that the particular form of flux control member illustrated is shown merely by way of example and that the member may have a large variety of forms which will readily suggest themselves to those skilled in the art.

In the form shown in Fig. 3, the extension member 21 is illustrated as encased in a tubular dielectric member 27 which is secured to a flange member 28 forming a multiple insulated flux control in which the upper portion of the conducting member is entirely encased in a dielectric cover.

In Fig. 4, the horn 15 is covered at its end by a tubular dielectric member 29 having the upper end closed and enlarged, as shown at 30, thus affording increased insulation at the point where the electro-static stress is greatest. An additional dielectric member 31 is secured to the upper portion of the member 30 by cement 32 providing a multiple control member. The cement 32 acts as a layer of conducting material between the two members 30 and 31.

In Fig. 5, the horn 15 is provided with a built-up or compound insulating member having a plurality of sections 33, the uppermost section having a rod of conducting material 34 projecting upwardly therefrom and carrying an insulator cover 35 at its upper end.

In Fig. 6, the insulator covering 35 is replaced by a metallic ball 36.

10 In Fig. 7, the horn 15 is provided with an insulator 38 of a still different shape which carries a metallic rod 39 having a knob 40 on its upper end. The knob 40 may be of insulating material encasing the upper end 15 of the rod 39, or it may be a metallic member similar to the ball 36 in Fig. 6.

In Fig. 8, the horn 15 carries a compound or built-up insulator 41 supporting a metallic extension 42 of the flux distributing member, upon the upper end of which is carried 20 a built-up insulator 43.

The insulator 43 may be covered with a rounded metallic cap 43' on the outer surface of the insulator. The metallic cap provides a flux distributing surface and prevents concentration of the flux at any one point on the outer surface of the insulator. It acts in a manner similar to the metallic 25 terminal ball shown in Figs. 6 and 7 and its 30 use in combination with the insulator 43 provides an effective means for preventing arcing due to concentration of the flux. The metal cap has advantages as outlined and is particularly important in increasing the reliability for one piece insulators or controls 35 of weak or poor dielectric strength. A crack in the control insulator due to shooting, depreciation or other causes may lower the pluming voltage like a sharp point 40 since the control extends into a strong field. If the end of the control has a surface of large curvature, the danger of pluming will not be so great but this necessitates a large internal diameter in the insulator greatly 45 increasing the size and cost of the insulator. Where a cap is placed on the outside of the insulator, the concentration of the flux is prevented and the desired result is secured without the necessity of increasing the size 50 of the insulator. Even where a large internal control is used, a defect in the outer dielectric covering will cause a concentration of stress and lower the pluming voltage. A metallic cap, however, will redistribute the 55 stress and tend to maintain a high pluming voltage even where the control insulator is punctured.

In Fig. 9, the horn 15 carries an elongated dielectric covering member 44, the upper end 60 of which is closed and encases the end of the horn 15.

The upper end of the dielectric member 44 is enclosed in a metallic cap 44' similar to the cap 43' shown in Fig. 8 and operating in 65 a similar manner.

In Fig. 10 the horn 15 is covered at its end by an insulator 45 and the upper portion of the insulator 45 is enclosed in a metallic cap 46 similar to those shown in Figs. 8 and 9. The cap 46 is in turn provided with 70 a dielectric cover or insulator 47 and the insulators 45 and 47 may be provided with flanges as shown. A metallic covering like 75 46 having well rounded surfaces between the two dielectric members of a compound control insulator will have particular advantage in that the metallic cover or cap insures a distribution of the lines of force and the outer dielectric cover forms an insulation to prevent excessive discharges or pluming. 80

In Fig. 11 a member 48 similar to member 44 in Fig. 9 covers the end of the horn 15 and secured to the upper end of the member 48 is a plurality of dielectric members 49 and 50 cemented to one another to provide a multiple flux control member. 85

In the form of the invention shown in Figs. 12 and 13, the lowermost insulator 12 supports an inverted bowl shape member 51 within which the saddle 14 is suspended by 90 a pin 52 and U bolts 53. The member 51 constitutes a flux shield for the saddle 14 and the supporting members and also provides an attachment for upwardly projecting horns 54 secured to the member 51 by 95 rivets 55. The horns 54 may be formed from hollow pipe and at their upper ends are shaped to receive insulating members 56. The insulating members 56 are built up multiple insulators having a plurality of dielectric members cemented together in a manner similar to pin type insulators. It will be seen that the horns 54 constitute flux distributing members which serve to regulate 100 the electrostatic gradient in the main string 105 and the multiple insulators 56 serve to prevent danger of excessive discharges from the ends of the horns. The multiple insulator provides added security against discharge by 110 increasing the insulation and providing reserve insulation in case one of the members should break down or be injured in any way. 115

Owing to the fact that it is possible to have less drop in voltage for a given distance along the control than for the same distance in the main insulator, the higher voltage of the control compared with that portion of the insulator adjacent thereto will permit a feeding in of electric flux or a discharge from the control to the insulator which would tend to take the stress off the lower portion of the main insulator nearest the conductor and increase the stress on the upper portion of the insulator, thereby tending to equalize the stress. 120

In my prior application, Serial No. 428, 488, an insulated flux control member is shown having a single insulating cover. As explained in that application, the flux con- 125 130

trol member provides a very efficient means for regulating the electrical gradient in an insulating member and for preventing pluming that is the formation of streamers into 5 the surrounding medium or discharge to ground from the insulating member or attachments. As was there explained, insulating the control permits placing of the same in a strong electro-static field which could 10 not otherwise be done owing to the danger of the uninsulated control arcing to ground or to the main insulator string where it would cut out or shunt a large part of the insulation. The interposition of dielectric 15 material in the path of such discharges increases the resistance of the path and hence prevents discharge or requires a higher voltage to cause such discharge. The insulated control can be used to prevent discharge 20 from clamps or from the conductor itself or from any object where the gradient is such that there is danger of discharge into the air or surrounding medium. The further the control extends into the field, the greater 25 will be the stress on the insulation over the same. Where the stress is very great a single insulating member may not have sufficient dielectric strength to withstand the stress. The present invention, as will be 30 readily understood, provides greater safety in this respect than is afforded by a single insulation. Various attachments may be used to provide multiple insulated flux control, as shown in the drawings. In Figs. 1 35 and 2 the multiple flux control is made up of two elements 17 and 23. In this case the two elements are separated by a conductor 21. The stress tending to break down the element 23 will not be so great as would be 40 the case if the elements 17 were omitted, so there will be less danger of puncture than where a single insulator is used. In Fig. 4 there is shown a multiple insulated flux control made up of two dielectric members. 45 This control may be of a variety of shapes, it being possible to use many of the ordinary pin insulators for this purpose. The nearer to the body of the insulating string the conducting element of the control is arranged, the greater will be its effect in influencing the stress distribution. Where this control extends well up along the insulator there will be a tendency to arc from the control to the string either while the insulator 50 is dry or when wet. Where there are several insulating members in the control, however, the difference in voltage between the different sections of the control and the main body of the insulator can be governed so that arcing 55 from the control to the main body of the insulator can be prevented or controlled as to amount of discharge so as to discharge and cause redistribution of stress. This is 60 of particular advantage in confined places 65 where the distance between the insulator and

control or field is relatively small so that there would be danger of the insulator on the flux control breaking down and arcing to ground if extended too far from or along the insulator. 70

Where the flux control has no direct connection to ground and is separated by air from any ground connection it will operate under all ordinary conditions even though its dielectric member may be damaged. The 75 flux control member need not support any other than its own weight. This enables the control member to be much more efficiently designed to obtain electro-static distribution of stresses than is possible with members in 80 the main insulator string.

A much greater influence can be exerted on the main string by connecting intermediate points in the series of flux control members to the electrodes in the main string by 85 a jumper or conductor, as shown at 48 in Fig. 1. A number of such conductors may be used to connect different points of the control members to various points along the insulator string. The points at which such conductors are attached will depend upon the relative electrical characteristics of the insulator and the control member and the result to be accomplished. This connection 90 48 may be such that it will be destroyed in case the power current passes over it to ground. For this purpose the connector may be made of fusible material so that the heat from a power current will cause it to blow. When a connector has been thus destroyed the remaining parts will continue to 95 operate as a flux control without direct connection to the main body. 100

It, of course, is evident that the flux control members may vary in number and in direction and be placed at either or both ends of an insulator element, such as ordinary transmission insulators, wireless insulators, bushings, or to protect bus bars or conductors which set up a strong field, from arcing to ground or between ends of terminals. The series arrangement of the parts of the control members permits of stepping down the voltage much more gradually than can be done where a single control element 105 is used. It is apparent, for instance, that in Fig. 1 the horn 15 will have the voltage of the conductor 13, but that there will be a drop in voltage over the insulator 17 from the horn 15 to the member 21. The member 21 will therefore have a potential lower than the line 13, but considerably higher than ground potential. There is therefore no sudden break in the potential as there is in the case of a single control member and the arcing voltage of the series is higher 110 than the single member. Consequently the danger of arcing is greatly decreased. 115

The controls may be insulated by flexible material, such as rubber hose or a series of 120 125 130

coverings. Owing to the deterioration of most flexible coverings its use would be limited to conditions where the advantage is very great or where only partial dependence is placed on the covering. An illustration of such use is shown in Fig. 4 where the member 15 is provided with a flexible insulating covering.

Where insulated flux controls are used it is not necessary that the end member terminates with an insulating cap. This member may be covered by a suitable metal covering or have an electrode terminating in a ball or other form. A suitable metal terminal having an extended smooth surface will, of course, be much more efficient than would be the case of an abruptly terminated rod from which the end insulation had been broken or cracked, or in which the end insulation broke down electrically permitting of a concentration of the stress at a point of discharge. When the flux control terminates with an electrode it can be used to charge the main insulator. A discharge may be set up between it and the main string by properly proportioning the gradient for the control and main string and regulating the discharge between the control and the string. Such a discharge can be made to control the stress where a difference between the stress in the insulator and control member is sufficient to cause a discharge between the control electrode and the body of the insulator.

The discharge from the control into the string would tend to cause greater stress to be set up in the portion of the insulator nearest the grounded connection. This would relieve the portion ordinarily under greatest stress nearest the line. This equalization by discharge may be made quite effective and fairly short distances used between the control and the main insulator as there would be a strong tendency to discharge at a point in the wave before the maximum stress is applied on the main insulator string. This is due to the fact that where the distance is such that a discharge may occur early in the wave the difference in potential would be materially reduced by the effective conductivity in the discharge arc. The current in the discharge arc will reduce as the equalization takes effect. As the current diminishes in the arc its resistance will increase greatly so that the arc may die out before maximum stress comes on the main insulator.

By taking advantage of the phase angle and the insulation in the air gap between the control member and main body of the insulator a very efficient arrangement may be made with a small amount of insulation in the control member, even where insulators are subject to storm or fog conditions causing heavy surface leakage. It is evident that if the effective insulation of the control

plus the effective insulation of the air gap at the point of discharge is equivalent to that of the portion of the insulator between the line and the discharge point the total insulation is not diminished by the presence of the control members. In other words, by utilizing the phase angle and the air gap between the control electrode and the body of the insulator the control may have much less insulation than the portion of the main insulator shunted by the discharge from the control.

The amount of discharge will be regulated by several factors, one of which will be the completeness of discharge of the control to the adjacent insulator member. Where this member is not covered by a metal cap or electrode the discharge may be very incomplete, even under wet conditions. Where the insulator is covered by a metal electrode more current will flow in the discharge arc and the equalization will be more complete. It is evident that under wet or severe conditions the discharge between the control and the main body of the insulator may be utilized to throw added stress on the upper or ground portion of the string or insulating element. While this arrangement may be used for normal operation, its greatest value would probably be for controlling unusual conditions, as its use in normal operation would necessitate some loss of energy, and considerable noise.

The series insulation in the control permits of a more extended use not only in controlling the flux, but in controlling the path of arcs of certain lines of discharge by placing the controls in position where it is not desired to permit the arc to start. Where the insulation terminates on a control or surface positioned in a strong field so that there is brush discharge, the danger of arcing to ground will be increased, as there will be a greater concentration of stress and more current in the streamers which stand out at the end of the insulation. This is due to the fact that the streamers tend to affect each other mutually limiting their respective currents to a considerable extent. The danger of arcing to ground where there is a persistent wave is greatly aggravated under conditions of this kind. Consequently where a single insulating element is used in the control, the hazard is much greater than where two are used in series, or where the end is terminated, or where the portion which may puncture is covered by an electrode, which will reduce the stress in the surrounding medium.

By the covering of the insulator on the control by a well rounded metal cap of proper design, a high concentration of stress at a puncture in the control insulator can be prevented from starting a plume until the stress reaches the pluming point of the metal

cap or covering which will be at a much higher voltage.

This covering permits of controls having small sections with comparatively sharp corners being used for mounting the control insulators. The result being that much smaller and cheaper insulators may be used which will have the higher pluming voltage where a control of large size is used but which would necessitate a large and more expensive insulator.

I claim:—

1. The combination with an insulator having a mechanical load supported thereon, of a flux control member therefor insulated by a plurality of dielectric members arranged in series and positioned one beyond the other in the electro-static field surrounding said insulator said flux control member being entirely supported from one end thereof and free from said mechanical load.
2. The combination with an insulator, of a flux control therefor, and a plurality of insulators for said flux control arranged in series with one another and separated from one another by conducting material said flux control member having a supporting connection at one end thereof.
3. The combination with an insulator, of a flux control therefor comprising a member having sections of conducting material positioned adjacent said insulator and separated from one another by a dielectric member said flux control member having a supporting connection at one end only thereof.
4. The combination with an insulator having a conductor connected thereto, of a flux control member for said insulator having supporting connection at one end only thereof and comprising a member of conducting material connected with said conductor and projecting therefrom into the electro-static field adjacent said insulator, said flux control member having a plurality of insulating members arranged in the path of the lines of force emanating therefrom, said insulating members being positioned one beyond the other in the direction of said lines of force.
5. The combination with an insulator having a conductor connected thereto and supported thereby, of a flux control member therefor comprising a member of conducting material connected with said conductor and extending therefrom into the field of force adjacent said insulator, a dielectric member arranged to cover a portion of said conductor, and a second conducting member positioned beyond said dielectric member in said electro-static field said flux control member being offset from the conductor supporting insulator and supported entirely at the end thereof connected with said conductor.
6. The combination with an insulator having a conductor connected thereto, of a flux

control member for said insulator free from the load imposed by said conductor and comprising alternating, conducting, and dielectric members arranged in series.

7. The combination with an insulator having a conductor secured thereto, of a flux control member connected with said conductor and extending into the electro-static field adjacent said insulator, said control member comprising a plurality of conducting members arranged in series and insulated from one another, said control member being free from stresses due to the load on said insulator.

8. The combination with an insulator having a conductor carried thereby, of a flux control member for said insulator having supporting connections at the end only thereof of adjacent said conductor and comprising a plurality of conducting members insulated from one another and arranged in series so that the various conducting members of said series will have potentials differing from one another due to their different positions in said electro-static field.

9. The combination with an insulator having a conductor supported thereby, said insulator constituting the entire support for the conductor at the point of connection therewith of a flux control member for said insulator comprising a member of conducting material secured to said conductor and projecting into the electro-static field surrounding said insulator, a dielectric member carried by said member of conducting material, and a second member of conducting material carried by said dielectric member and supported in said electro-static field in a position beyond said first member of conducting material so that said second member of conducting material will have a potential different from said first member of conducting material due to its position in said field.

10. The combination with an insulator having a conductor supported thereby, of a flux control member connected with said conductor and extending into the electro-static field adjacent said insulator, said flux control member having the end thereof opposite said conductor unsupported except by its connection with said conductor, and a dielectric member arranged to separate said control member into sections insulated from one another.

11. The combination with an insulator having a conductor supported thereby, of a flux control horn projecting from said conductor in the general direction of said insulator, said horn comprising a plurality of sections of conducting material, said sections being insulated from one another by dielectric material.

12. The combination with an insulator having a conductor supported thereby, of a

6

flux control member for said insulator comprising a rod connected with said conductor and entirely supported from the end thereof adjacent said conductor, a dielectric member arranged to cover a portion of said rod at the end thereof, a second conducting member supported from said dielectric member and insulated from said rod, and means carried by said second conducting member 10 for preventing discharge therefrom, due to concentration of electro-static lines of force emanating therefrom.

13. The combination with an insulator having a conductor supported thereby, of a 15 flux control member connected with said conductor and extending into the electro-static field surrounding said insulator, said flux control member being entirely supported from the end thereof connected to 20 said conductor and comprising a plurality of alternating, conducting and dielectric members arranged in series with one another.

14. In combination, an insulator having 25 a conductor connected therewith, and a flux distributor for feeding flux to said insulator at points removed from said conductor to regulate the potential gradient along said insulator, said distributor comprising a 30 series of conductor and insulator members alternating with one another said insulating members being graded in size.

15. In combination, an insulator having a conductor connected therewith, a flux distributing member extending from said conductor into the surrounding electro-static field and being supported from the end thereof connected with said conductor, a dielectric member interposed in the path of 40 lines of force emanating from said distributing member, and a member of conducting material extending beyond said dielectric member in series with said first-mentioned distributing member and insulated therefrom.

16. In combination, an insulator having conductors of different potentials connected therewith, and a flux distributor connected with one of said conductors and extending 50 toward but free from the other thereof, said distributor comprising a series of alternating, conductor and insulator members.

17. In combination, an insulator having conductors of different potentials connected 55 therewith, and means for regulating the potential gradient along said insulator between said conductors, said means comprising a flux distributor having a series of alternately arranged conductor and insulator members, said distributor having a conductor member thereof connected with one of said first-mentioned conductors and extending from said conductor in the general direction of said insulator but free from 65 the other first-mentioned conductor and ar-

ranged to feed flux to said insulator at points along its length.

18. The combination with an insulator having conductors of different potentials connected with opposite portions thereof, of 70 a flux distributor for said insulator comprising a series of alternate conducting and insulating members, said distributor having connection with one of said conductors at one end thereof, but arranged with an air 75 gap separating it from the conductor at the opposite end of said insulator.

19. The combination with an insulator comprising a plurality of units, of a flux control member therefor comprising a plurality of conducting members insulated from one another, and an electrical connection between one of the units of said insulator and a conducting member of said flux control, said flux control being supported independent of said electrical connection.

20. The combination with an insulator having a plurality of units and connected with a conductor, of a flux control connected with said conductor and extending into the electrostatic field adjacent said insulator, said flux control comprising a plurality of conducting members insulated from one another, and means for electrically connecting one of the conducting members for said flux control with one of the units of said insulator, said conducting member having a covering of dielectric material for the extremity thereof, the connecting members being insulated from the conductor supported by said insulator.

21. The combination with an insulator comprising a plurality of units and a conductor supported thereby, of a flux control comprising a plurality of alternately arranged conductor and insulator members, one of which is connected with said conductor, and means for electrically connecting a conductor member of said control removed from said supported conductor with a unit of said insulator also removed from said supported conductor, the conductor member so connected being superimposed by one of the insulator members of said control.

22. The combination with an insulator having a plurality of units and a conductor supported thereby, of a flux control connected with said conductor and extending into the electro-static field adjacent said insulator, said flux control comprising alternately arranged conductor and dielectric members in series, and means for electrically connecting one of said conductor members removed from said supported conductor with said insulator at point removed from said conductor, said electrical connecting means being composed of material which will be broken by excessive current.

23. The combination with an insulator of 130

a control member therefor comprising a conducting body, a dielectric member enclosing a terminal portion of said body and a metallic cover for said dielectric member having 5 an extended outer surface.

24. The combination with an insulator of a control member therefor comprising a conducting body, arranged adjacent said insulator, a dielectric member for insulating a

portion of said conducting body and a 10 metallic cap on said dielectric member having a rounded extended outer surface for distributing lines of force emanating therefrom.

In testimony whereof I have signed my 15 name to this specification on this 26th day of May, A. D. 1921.

ARTHUR O. AUSTIN.
